(57) **CLAIM**

The ornamental design for a bracelet as shown and described.

DESCRIPTION

1. Bracelet

1.1 : Perspective

1.2 : Front

1.3 : Back

1.4 : Top

1.5 : Bottom

1.6 : Left

1.7 : Right

Rigid octagonal oval bracelet shape, consisting of two symmetrical parts, each with four facets (i.e. eight facets), of different sizes but symmetrically identical to the opposite facet; the facets have unpaved beveled edges of identical width on each side; the two symmetrical parts of the bracelet are connected at one end and enable the bracelet to be opened and closed at the other; the flat part of the three upper facets of the jewel is paved with two rows of fine diamonds; the largest facet comprises, on the left, an unpaved stud in truncated pyramid shape.
